UNITED STATES PATENT OFFICE.

ALFRED M. ZIEGLER, OF NEWTON, MASSACHUSETTS.

GARMENT SUPPORTER.

Application filed May 17, 1921. Serial No. 470,347.

To all whom it may concern:

Be it known that I, ALFRED M. ZIEGLER, a citizen of the United States, and a resident of Newton, in the county of Middlesex 5 and State of Massachusetts, have invented an Improvement in Garment Supporters, of which the following description, in connection with the accompanying drawings, is a specification, like characters on the drawings representing like parts.

This invention relates to garment supporters and the object is to provide certain improvements in devices of this nature which will make them more economical to manufacture and more attractive for use. Specific improvements are particularly adapted to garment supporters utilizing a metallic spring gear.

My invention will best be understood by reference to the following description of an illustrative embodiment thereof shown by way of example in the accompanying drawings, wherein:

Fig. 1 shows a portion of a shoulder piece 25 and one of the ends of a suspender having features illustrative of my invention;

Fig. 2 is a section on the line 2—2 of Fig. 1;

Fig. 3 is a section on the line 3—3 of Fig. 1;

Fig. 4 is a view of the back portion of a pair of suspenders; and

Fig. 5 is a section on the line 5—5 of Fig. 4.

Referring to Figs. 1, 2 and 3 of the drawings, I have there shown my invention as applied to a suspender embodying the shoulder piece 5 attached to the button engaging member 7 by a connection more particularly embodying my improvements, in this instance including a metallic spring device whereby the desired resiliency in the suspender is provided for.

I may attach to the shoulder piece 5 a tubular pocket 9 which preferably takes the form of a section of seamless woven tube or tubular webbing which may be attached to the shoulder piece in any desired manner, in the present instance the end thereof being looped through the ring 11 and sewed to itself. The seamless tube provides a pocket to receive a spring gear by which the button engaging element 7 is supported and I have herein illustrated a cross-bar 13 at the lower end of the pocket in which works a draw-bar 15 supported by a spring 17. The

draw-bar in the illustrated example consists of an endless loop of flexible cord trained through eyes 19 at the ends of the cross-bar 13 and the spring 17 is a helical spring surrounding the portion of the loop above the cross-bar and finding a bearing on the eyes 19. The lower portion of the loop projects from the tubular pocket 9 for attachment to the garment engaging member 7.

The use of a seamless woven tube to provide a pocket to house the spring gear gives an attractive and finished appearance to the article and requires a minimum of expense in handling to complete the supporter. The 70 pocket is secured to the body engaging portion of the supporter 5 very conveniently as by sewing and to provide a finish at the lower end of the pocket and also to support the spring gear by means of the cross-bar 75 13 I preferably invert the end of the tube as best shown in Fig. 2, and secure together the sides of the tube at this end, preferably by the stitching 21 to support the middle portion of the bar 13 and at the same time 80 to finish off the lower end of the tube in the manner of a hem. The side portions of the draw-bar loop project from the end of the tube between the sides thereof and the stitching.

To connect the loop 15 to the garment, as through the medium of the button engaging member 7, I preferably provide a strip 23 of fairly stiff material such as fairly heavy leather which is doubled through the projecting portion of the loop 15. The strip 23 is notched at each side as shown at 25 (see Fig. 3) to provide a relatively narrow neck portion where it crosses the loop 15, the sides of the loop being closely received in 95 these notches. The ends of the leather strip 23 may be secured in any desired manner and herein they are looped around the member 7 and sewed together by stitching 27. When strain is applied to the strip 23 100 the tendency is to pull it through the loop 15 and since the loop rests in the notches 25 there is provided by the relatively stiff leather a sort of cross-head or T engaging the sides of the loop which takes up some of 105 the strain so that it is not transmitted to the stitching 27 in such measure as would be the case if the strip could run freely through the loop. The neat and attractive finish provided by stitching is thus provided 110 for without the necessity of making the stitching unduly heavy with resulting addi-

tional expense. In the example illustrated wherein the element 23 is not directly attached to the button but suspends a loop 7, the loop 7 may engage a neck of the element 23 as shown in the same manner as the loop 15.

In the example of the invention shown in the drawing the tube 9 is a separate piece attached to the shoulder strap 5 by the link 10 11. It obviously might be a continuation of this shoulder piece and in the construction of a pair of suspenders as shown I prefer to utilize fabric tubes for the shoulder straps 5. The main body portion of these 15 will have the appearance of the ordinary flat webbing and considerable advantage arises from their use in suspenders. As shown in Fig. 4 the two tubular straps may go over the shoulders and be crossed in the 20 back in the usual manner, that which passes over the left hand shoulder being attached to the right hand button at the back of the trousers and vice versa, and the two tubes simply secured together where they cross 25 as by sewing 29 or the like without the addition of any extra parts and at the same time pockets are provided at the extremities of the straps each to receive a spring gear such as is shown in Fig. 1 for making connection with the buttons on the trousers. 30 Herein I have shown buttonhole loops of leather suspended from the draw-bar loop 15 in a manner similar to that in which the connecting member 23 is suspended in Figs. 35 1, 2 and 3.

Having thus described in detail the particular embodiment of my invention shown by way of example in the accompanying drawings, the features exemplified thereby 40 which I claim as new and desire to secure by Letters Patent I shall define in the following claims:

1. A garment supporter comprising a garment engaging portion and a sustaining portion, one of said portions terminating in a fabric tube, a cross-bar at the free end of the tube, the face and back of the tube at that end being secured together for a part of their width to support the cross-bar while 45 providing space to accommodate the draw-bar hereinafter mentioned, the whole providing a structure free of fullnesses or angular hems, a draw-bar projecting from the tube, resilient means in the tube cooperating 50 with the cross-bar to sustain the draw-bar,

the draw-bar being connected to the other of said portions of the supporter.

2. A structure as defined in claim 1 wherein the free end of the tube is turned and the face and back stitched together 60 whereby to provide for the support of the cross-bar and the accommodation of the draw-bar as specified and likewise to provide a hem-like finish for the end of the tube. 65

3. A garment supporter comprising a garment engaging portion and a sustaining portion, one of said portions terminating in a seamless fabric tube, the free end of the tube being turned and the front and back 70 seamed together for a portion of their width partially to close the tube and to provide openings to the interior thereof, a spring gear in the tube supported therein by the closed portion of said end and having a part 75 projecting through said openings, said part being connected to the other of said portions of the supporter.

4. A garment supporter comprising a garment engaging portion and a sustaining portion, one of said portions terminating in a seamless fabric tube, the front and back of the tube at the free end thereof being secured together for a portion of their width 80 partially to close the tube and to provide 85 openings to the interior thereof, a spring gear in the tube supported therein by the closed portion of said end and having a part projecting through said openings, said part being connected to the other of said 90 portions of the supporter.

5. Suspenders comprising a pair of shoulder straps of seamless tubular fabric crossed and secured together at the back and means for attaching the straps to the garment 95 comprising spring gear received and supported in the tubular ends of the straps and projecting from the ends thereof for attachment to the garment.

6. A suspender comprising a shoulder engaging strap of seamless tubular fabric and means for attaching the same to the garment comprising spring gear received and supported in the tubular end of the strap and projecting from the end thereof for 105 connection with the garment.

In testimony whereof, I have signed my name to this specification.

ALFRED M. ZIEGLER.
